UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-METAL PUMP.

Application filed June 29, 1922. Serial No. 571,689.

To all whom it may concern:

Be it known that I, HENRY F. BECHMAN, a citizen of the United States, residing at Battle Creek, in the county of Calhoun and State of Michigan, have invented certain new and useful Improvements in Stereotype-Metal Pumps; and I hereby declare that the following is a full, clear, and exact description thereof, reference being had to the accompanying drawings, which form part of this specification.

This invention is a novel improvement in pumps for pumping molten metal or the like, and is particularly designed for pumping molten stereotype metal from an ordinary melting pot into the stereotype plate casting boxes or molds.

The principal objects of the invention are to provide a pump which will supply a uniform amount of molten metal at each operation regardless of minor variations in the level of the molten metal in the pot. Also to provide a pump whereby the amount of metal pumped at each operation can be accurately regulated; also to provide a pump which will be practically self-cleaning, and not liable to clog or choke.

I will explain the invention as embodied in a pump for pumping molten stereotype metal, to enable others to readily understand, adopt and use the invention; but I do not consider the invention limited to pumps for molten metal, as it is capable of being utilized in pumps for other fluids. In the claims following the description the essentials of the invention, the novel features of construction, and novel combinations of parts, for all of which protection is desired, are summarized.

40 In said drawings:

Fig. 1 is a sectional view of the pump in operative position on an ordinary melting pot.

Fig. 2 is a top plan view of Fig. 1.

45 Fig. 3 is a sectional view showing the pump discharging fluid.

In the construction shown the pump comprises a vertically reciprocable cylinder or ladle 2, open at its upper end and closed at bottom, which is connected to and suspended on the lower end of a rod 2^a that extends upwardly through an axial opening in the pump piston 3, and through the tubular stem of said piston, and its upper end is guided in 50 an eye on the upper end of a bracket 5, which

may be formed with or attached to the upper side of a bracket 6 which is secured to the top flange of the pot 1, or other suitable support adjacent the pot, bracket 6 projecting inwardly over the top of the pot.

60 The melting pot 1, illustrated in the drawings, may be of the usual construction used in connection with a suitable furnace for melting metal for casting stereotype plates.

The ladle may be guided in its vertical movements by an annular skimmer and ladle guide 7 which is attached to the under side of the inwardly extending portion of the bracket 6, and is provided with interior radially disposed lugs 7^a adapted to engage 70 the exterior surface of the ladle and guide the same in its rising and falling movements.

75 The ladle can be raised or lowered by any suitable means. As shown, its supporting rod 2^a has a rack 2^b on its upper end which is engaged by a pinion 4^b on a shaft 4 one end of which is journaled in the upper end of the bracket 5, and its other end is supported on a bracket 5^b attached to the top of the pot, or other suitable support, in line 80 with the bracket 5, (see Fig. 2). Shaft 4 can be rotated by a crank 4^c or other suitable means.

85 The pump piston 3 is of such diameter as to fit neatly and closely within the interior of the ladle 2 when entered therein. This piston is preferably slightly concaved on its under side and has a central opening which communicates with the bore of a tubular stem 3^a by which the piston is connected to the under side of the inwardly extending portion of the bracket 6. The piston 3 and stem 3^a are in axial alinement with the ladle 2 and the rod 2^a extends axially through the piston and stem 3^a, and 90 through an opening 6^a in the end of the bracket 6 to which the stem 3^a is attached.

95 Mounted upon the bracket 6^a above the sleeve 3^a is a spout 8 which has an opening in the under side of its rear end communicating with the opening 6^a, and an opening in its upper side for the passage of the stem 2^a; said spout projects outwardly and inclines downwardly to its mouth so that the molten metal may be discharged from the 100 spout into a casting box or other suitable receiver, not shown.

105 In this invention the piston is stationary and the cylinder or ladle is reciprocated. The parts are so arranged that the lower 110

portion of the annular skimmer and ladle guide 7 will be below the level of the molten metal in the pot; and the ladle when in its lowermost position (as shown in Fig. 1) 5 will also be below the lowermost practical level of the molten metal in the pot. In its lowered position the upper end of the ladle lies within the lower end of the guide 7, and below the fixed piston 3 as shown in Fig. 1. 10 The lugs 7^a guide the ladle, and ample space is left between the lugs for the free passage of the molten metal from beneath upwardly into the annular skimmer and guide 7, and thence into the ladle. By this construction 15 the surface metal is excluded from the ladle 3 by the annular skimmer-guide 7, the ladle being filled by molten metal which flows upwardly from beneath the skimmer-guide into the skimmer-guide and up over the 20 upper edge of the ladle into the latter. By withdrawing the metal from below the surface of the metal in the pot no dross or scum floating on the surface will enter the ladle. 25 The amount of metal pumped at each full upward stroke of the ladle is always the same, regardless of the level of the metal in the pot, unless it falls below the minimum limit of the level of molten metal; this limit 30 being the top of the ladle when in its lowest position, as shown in Fig. 1.

Suitable means are provided for limiting the reciprocatory movements of the ladle. As shown, a collar 2^c on rod 2^a is adapted to 35 engage the bracket 5, and limit the upward movement of the rod and ladle; and a collar 2^d on rod 2^a is adapted to engage the top of the spout 8 and limit the downward movement of the rod and ladle, see Fig. 1. By 40 adjusting the said collars or stops the amount of metal discharged at each operation of the pump can be accurately regulated, so that just the amount of metal required for the work in hand will be discharged at each operation.

When used for pumping molten metal the pump is self-skimming. The ladle is filled only with the purest and best of the molten metal and if in any interval between operations of the pump any slight scum should form on the surface of the metal in the annulus this scum would drop off and would not enter the ladle, because as the ladle rises the metal in the annulus is displaced, the 50 metal in the annulus above the ladle overflowing the sides of the ladle and passing down the outside of the ladle into the pot as the ladle rises. When the ladle ascends any scum formed in the annulus will be projected out of it by the ladle.

The bore of the fixed stem of the piston is preferably tapered as shown and the spout is inclined so that there is no place for molten metal to lodge and chill, and the 55 pump fluid passages will remain clean. The

pump can be operated with great economy and efficiency.

Obviously various changes might be made in the form and construction of parts while retaining the essential novel features of the 70 invention, and while the pump is particularly designed for handling molten metal the invention is also useful and adaptable for pumping other fluids.

What I claim is:

1. In a pump, a reciprocable ladle, a stationary piston, means for moving the ladle to telescope the piston and thereby discharge the fluid from the ladle; and a member surrounding the ladle whereby the fluid is 80 caused to flow upwardly between the member and the ladle in order to enter the ladle.

2. A pump comprising a ladle having an open upper end, a piston fixed above the ladle having a discharge opening, means for moving the ladle toward the piston to force the fluid from the ladle through the opening in the piston; means for directing fluid from 85 said opening to the point of discharge; and a member surrounding the ladle whereby the fluid is caused to flow upwardly between the member and the ladle in order to enter the ladle.

3. In a pump, a reciprocable ladle, a stationary piston having an axial opening, a 95 tubular stem supporting the piston; means for moving the ladle to telescope the piston and thereby discharge the fluid from the ladle through the piston and stem; and a member surrounding the ladle whereby the 100 fluid is caused to flow upwardly between the annulus and the ladle in order to enter the ladle.

4. In combination with a fluid container, a ladle having an open upper end and closed at bottom, a piston fixed above the ladle and having a discharge opening; means for causing the ladle to telescope the piston and eject the fluid from the ladle through the opening 105 in the piston; means for directing the fluid from said opening to the point of discharge; and an annular member surrounding the 110 ladle and having its lower end submerged in the liquid whereby the fluid is caused to flow upwardly between the member and the ladle 115 in order to enter the ladle.

5. In combination with a metal melting pot; a ladle open at its upper end and closed at bottom; a stationary piston above the open end of the ladle having a discharge opening; means for raising the ladle to telescope the piston and force the metal therein to escape through the opening in the piston; means for conducting the molten metal from the opening in the piston to the point of discharge; and a member surrounding the 120 ladle whereby the fluid is caused to flow upwardly between the member and the ladle in order to enter the ladle.

6. In a metal pump, a pot, a reciprocable

ladle therein, a stationary piston located above the level of the molten metal in the pot, and means for moving the ladle to telescope the piston and thereby discharge the molten metal from the ladle.

7. In a pump as set forth in claim 6, a member surrounding the ladle whereby the fluid is caused to flow upwardly between the member and the ladle in order to enter the ladle.

10 8. A metal pump comprising a pot, a ladle having an open upper end, a piston located and fixed above the level of the fluid and above the ladle when the latter is lowered, said piston having a discharge opening, means for moving the ladle toward the piston to force the fluid from the ladle through the opening in the piston, and means for directing fluid from said opening to the 20 point of discharge.

25 9. In a pump, as set forth in claim 8, a member surrounding the ladle whereby the fluid is caused to flow upwardly between the member and the ladle in order to enter the ladle.

10 10. In a metal pump, a pot, a reciprocable ladle, a stationary piston having an axial opening, said piston being located above the level of the molten metal in the pot, a tubular stem supporting the piston, and means 30 for moving the fluid from the ladle through the piston and stem, substantially as described.

11. In a pump as set forth in claim 10, a member surrounding the ladle whereby the fluid is caused to flow upwardly between the annulus and the ladle in order to enter the ladle.

12. In combination with a metal melting pot, a ladle having an open upper end and closed at bottom, and normally submerged in the fluid, a piston fixedly located above the level of the metal in the pot and above the ladle when the latter is submerged, said 45 piston having a discharge opening; means for causing the ladle to telescope the piston and eject the fluid from the ladle through the opening in the piston, and means for directing the fluid from said opening to the 50 point of discharge.

13. In combination with mechanism as set forth in claim 12, an annular member surrounding the ladle and having its lower end submerged in the liquid whereby the 55 fluid is caused to flow upwardly between the member and the ladle in order to enter the ladle.

14. In combination with a metal melting

pot; a ladle adapted to be submerged in the pot and open at its upper end and closed at bottom; a stationary piston located above the level of the metal in the pot, and above the open end of the ladle when the latter is lowered, said piston having a discharge opening; means for raising the ladle to telescope the piston and force the metal therein to escape through the opening in the piston, and means for conducting the molten metal from the opening in the piston to the point of discharge.

15. In combination with mechanism as set forth in claim 14, a member surrounding the ladle whereby the fluid is caused to flow upwardly between the member and the ladle in order to enter the ladle.

16. In combination, a ladle having an open upper end and closed at bottom, and adapted to be normally submerged in the fluid to be pumped; a piston fixed above the ladle and fluid level and having a discharge opening; means for causing the ladle to telescope the piston and eject the fluid from the ladle through the opening in the piston; means for directing the fluid from said opening to the point of discharge; and a skimming annulus surrounding the piston and ladle and having its lower end submerged in the fluid; whereby the fluid is caused to pass upwardly between the annulus and the ladle in order to enter the ladle.

17. In combination, a ladle adapted to be submerged and open at its upper end and closed at bottom; a stationary piston above the open end of the ladle having a discharge opening; means for raising the ladle to telescope the piston and force the metal therein to escape through the opening in the piston, a spout for conducting the molten metal from the opening in the piston to the point of discharge, and an annulus surrounding the piston and ladle whereby the fluid is caused to flow upwardly between the annulus and the ladle in order to enter the ladle.

18. In a pump having a ladle and a relatively movable piston, means whereby the fluid is caused to pass upwardly around the ladle in order to enter it.

19. In a pump, a reciprocable ladle, a stationary piston, and means whereby the fluid is caused to pass upwardly between the member and the ladle in order to enter it.

In testimony that I claim the foregoing as my own, I affix my signature.

HENRY F. BECHMAN.
